UNITED STATES PATENT OFFICE.

FRANK J. LEARMAN, OF BUFFALO, NEW YORK, ASSIGNOR TO ANDREW R. KOEHLER, OF BUFFALO, NEW YORK.

BLACKLEADING-MACHINE

No. 896,400.

Specification of Letters Patent.

Patented Aug. 18, 1908.

Application filed May 11, 1908. Serial No. 432,188.

To all whom it may concern:

Be it known that I, FRANK J. LEARMAN, a citizen of the United States, residing at Buffalo, in the county of Erie and State of New York, have invented a new and useful Improvement in Blackleading-Machines, of which the following is a specification.

This invention relates more particularly to spout actuating mechanisms for machines which are used in electrotype work for coating the wax matrices with black lead, but the invention is applicable to actuating means for any movable part where a universal movement thereof is desired.

In matrix coating machines, as commonly used in electroplating work, the wax matrix is placed in a bath of finely pulverized plum-bago, commonly called "black lead", and water. A suitable pump is employed for forcing the liquid through a movable discharge spout against the surface of the matrix in the bath to coat the same with the black lead, and this pump preferably takes the liquid from the bath so as to keep the same liquid in circulation.

The object of this invention is to provide an actuating mechanism for the movable discharging spout which will be simple in construction and positive in operation and which will automatically move the discharge spout back and forth in different directions, or universally over the matrix so that the entire surface of the same will be completely and evenly coated with the black lead.

In the accompanying drawings: Figure 1 is a perspective view of a matrix coating machine provided with a spout actuating mechanism embodying the invention. Fig. 2 is a plan view thereof, partly in section, showing various different positions of the discharge spout in dotted lines. Fig. 3 is a sectional elevation thereof in line 3—3, Fig. 2.

Like letters of reference refer to like parts in the several figures.

A represents the tank for containing the black lead bath in a matrix coating machine, B a pump connected therewith by an intake pipe *b* and provided with a discharge pipe *b'*, a portion at least of which is flexible and terminates in a suitable nozzle *b''*. C represents a wax matrix which rests in the tank beneath the nozzle *b''* upon a support or frame D. All of these parts may be of any suitable or usual construction.

E and F represent vertical shafts jour-

naled in suitable bearings *e f* on two sides of the tank A and provided at their upper ends with cranks *e'* and *f'* which are connected by pitmen or links *e''* and *f''* to the free end of the discharge spout. The pitmen are preferably connected by ball and socket joints *e'''* and *f'''* to a clamp *g* embracing the spout to allow a free movement of the spout in different directions.

Any suitable means may be employed for driving the vertical shafts E and F. In the construction shown, drive shafts H and I are journaled in suitable bearings on the sides of the tank A at which the crank shafts E and F are located, and are connected by intermeshing bevel gears *h* and *i* which cause them to turn in opposite directions. One of the shafts, for instance the shaft H, is provided with tight and loose pulleys K for a belt for driving this shaft. The drive shafts H and I are connected to the crank shafts E and F by intermeshing bevel gear wheels *l* and *l'*, respectively. This arrangement of the shafts and connecting gears causes the vertical crank shafts to revolve in opposite directions, and the gears are so proportioned that the crank shafts are driven at different speeds. The cranks *e'* and *f'* are also preferably of different lengths. By reason of this arrangement of the shafts and gearing, the cranks continually change their relation to each other and shift the discharge spout to which they are connected in different directions, and to different positions. As the cranks travel at different speeds, they can only occupy the same relation to each other after a number of revolutions of their cranks, depending upon the relative speed of the same. The spout is therefore moved back and forth over the matrix in different paths and eventually repeatedly covers all parts of the matrix. A few of the many different positions of the cranks and discharge spout are shown by full and broken lines in Fig. 2. The same results can be secured by any suitable drive mechanisms for rotating the cranks in opposite directions at different speeds. The parts of the actuating mechanism should be proportioned and arranged to give the most effectual movement of the spout and prevent the same from assuming a dead center position or coming into contact with the walls of the tank.

I claim as my invention:

1. In a black-leading machine the combi-

nation with a movable discharge spout, of
cranks connected to said spout, and means
for revolving said cranks at different speeds
whereby the spout is shifted in a variety of
5 different directions, substantially as set
forth.

2. In a black-leading machine the combination
of a tank, a movable spout for dis-
charging liquid against the surface of a ma-
trix in said tank, cranks located on different
10 sides of the tank and connected to said spout,
and means for revolving said cranks at differ-
ent speeds, whereby the spout is shifted to
various different positions in the tank, sub-
stantially as set forth.

3. In a black-leading machine the combination
of a tank, a movable spout for dis-
charging liquid against the surface of a ma-
trix in said tank, cranks located on different
20 sides of the tank and connected to said spout,
and means for revolving said cranks in oppo-
site directions at different speeds whereby
the spout is shifted to various different posi-
tions in the tank, substantially as set forth.

25 4. In a black-leading machine the combi-
nation of a tank, a movable spout for dis-
charging liquid against the surface of a ma-
trix in said tank, cranks located on different
sides of the tank, links connected to the
30 cranks, universal joints connecting the links

to the spout, and means for revolving said
cranks in opposite directions at different
speeds whereby the spout is shifted to various
different positions in the tank, substantially
as set forth.

35

5. In a black-leading machine the combi-
nation of a tank, a movable spout for dis-
charging liquid against the surface of a ma-
trix in said tank, two actuating devices con-
nected to said spout for controlling the move-
ment thereof, and mechanism for producing
a relatively different motion of said actuating
devices whereby they cause an irregular
movement of said spout, substantially as set
forth.

45

6. In a black-leading machine the combi-
nation with a tank, a movable discharge
spout emptying into said tank, actuating
arms connected with said spout and arranged
at an angle to each other, and means for
moving said arms at different speeds where-
by said spout is shifted to various different
positions in the tank, substantially as set
forth.

Witness my hand, this 7th day of May, 55
1908.

FRANK J. LEARMAN.
